UNITED STATES PATENT OFFICE.

SETH CLELLAN GUNN, OF CLOUDCROFT, NEW MEXICO.

METALLIC RAILWAY-TIE.

1,124,423.

Specification of Letters Patent.

Patented Jan. 12, 1915.

Application filed May 6, 1914. Serial No. 836,732.

To all whom it may concern:

Be it known that I, SETH CLELLAN GUNN, a citizen of the United States, residing at Cloudcroft, in the county of Otero and State 5 of New Mexico, have invented certain new and useful Improvements in Metallic Railway-Ties, of which the following is a specification, reference being had to the accompanying drawings.

10 This invention relates generally to railway ties, and more particularly to those of the metallic type.

The object of the invention is, in a ready and practical manner, so to construct a tie 15 as to render it self-anchoring whereby to insure its ready assemblage with the road-bed, thereby to eliminate loosening of the rails with attendant danger of accident.

A further object is to improve the construction of the tie in such a manner as to 20 render it possible to retain the ballast in place between the ties against danger of it being washed out from rains or freshets, and further to deaden or absorb sounds in- 25 cident to the passage of rolling stock, and the thumping sounds usually attending the employment of metallic ties will be eliminated.

A further object is to improve the manner 30 of retaining the rails upon the ties, so as practically to eliminate any danger of the holding bolts working loose from jars or vibrations.

With the above and other objects in view, 35 as will appear as the nature of the invention is better understood, the same consists in the novel construction and arrangement of parts of a metallic tie as will be hereinafter fully described and claimed.

40 In the accompanying drawings forming part of this specification, and in which like characters of reference designate corresponding parts: Figure 1 is a top plan view of a section of railway equipped with a tie 45 of the present invention; Fig. 2 is a transverse sectional view, partly in elevation, through one of the ties; Fig. 3 is an end view of the tie and the rail combined therewith; Fig. 4 is a perspective detail view of the tie; and Figs. 5 and 6 are detail views of certain parts of the appliance.

The tie is constructed of cast steel or malleable cast iron, is of truncated pyramidal form in cross section and is provided at each 55 end with two oppositely disposed wings 2, that occupy planes at right angles to the

longitudinal axis of the tie. By reason of the contour of the tie in cross section, it will be seen that when it is firmly positioned upon the road-bed the inclined sides of the tie will serve to anchor it firmly in position, this anchoring being accentuated by the lateral pressure exerted against the sides by the ballast.

The ties are connected by head plates or 60 boards 3, the upper edges of which are preferably somewhat curved, and extend slightly above the upper face of two adjacent ties, the ends being inclined to correspond to the opposed sides of the ties, and these head 65 plates are secured in position by bolts 4 that project through openings 5 in the head plates, 6 in the wings and 7 in the nut locks, the nuts 8 being engaged with the outer sides of the latter to clamp the parts firmly together. The heads of the bolts 4, which are disposed against the inner sides of the wings, are square and engage with the opposed faces of the ties, thus to be held 70 against turning when the nuts are being seated. The nut locks, to which reference has been made, are constructed each of a strip of metal that is normally flat and is bent upon itself and has one end inturned, when positioned, to provide a lip 9 which engages the 75 inner wall of the tie so as to aid in reinforcing the ties against working apart, the outer member constituting a nut-lock employing three tongues 10 that are designed to be bent up against the sides of the nut.

One of the features of the invention resides in deadening the sound due to the passage of trains over the tracks, and this is accomplished by the provision of plugs 11 that fit snugly within the ends of the ties, 80 and are held therein by barbed spikes driven through the openings 12 in the sides of the ties adjacent to their ends. Where the ties are used in lowlands where freshets occur, the plugs may be removed in rainy seasons 85 to permit the water to pass through the ties, while the head plates or retaining boards will prevent the ballast from being washed out. As will be obvious, the employment of the retaining boards is only necessary in 90 cross country runs, as in all yards and terminals the surface of the ground is brought to a level with, or a little above, the tops of the ties. The road-bed when completed should be sprinkled with crude oil to prevent 95 rusting of the material.

The rails 13 are held combined with the

sides of the ties by means of buttons or 5 clips 14, each of which is constructed preferably from a length of malleable iron bent upon itself to provide two tongues 15 and 16, the latter of which is the longer, the two 10 tongues being provided with orifices. The shorter tongue is designed to bear against the edges of the base of the rail, while the longer tongue overlies and bears against the upper side thereof and extends close to the web, and a bolt 17 passes through an elongated opening 18 in the tie, and through a clip 14 and a nut lock 19, and carries a nut 20 for locking the clip in place, the same arrangement being observed 15 in each of the fastening appliances for the rails, the nut preferably being of a size to overlap the base of the rail.

In addition to the feature of self-anchoring and deadening the sound, the tie herein 20 described will be as effective in preventing the tracks getting out of line as will the ordinary wooden ties commonly employed, so that the objection heretofore urged against 25 the employment of metallic ties is obviated.

From the foregoing description it will be seen that although the improvements herein set forth are simple in character, they will coact in the production of a thoroughly 30 efficient and reliable form of railway tie, and one which will have all of the advantages and none of the disadvantages of an ordinary wooden tie.

Having thus described my invention, what 35 I claim is:

1. A railway tie having oppositely directed wings at its ends, and means carried by the wings whereby the tie may be connected to adjacent ties.

40 2. The combination with a series of hollow metallic ties each having oppositely disposed wings at its ends, of plates disposed between the ties and secured at their opposite ends to the opposing wings of adjacent ties, each of said ties having inclined side 45 walls, and the opposite end edges of the plates being inclined to the inclination of the opposed sides of the ties.

3. A hollow metallic railway tie having inclined side walls by means of which the tie is securely anchored under the ballast, and said tie having oppositely directed apertured wings at its ends whereby the tie may be connected to adjacent ties of a track. 50

4. The combination of a series of ties, 55 each having at its ends outturned wings, of head plates rigidly secured to the wings and serving to retain the ties properly spaced and to prevent dislodgment of the ballast.

5. The combination with a series of hollow metallic ties, each provided at its ends with outstanding wings, of head plates disposed between the ties and bearing against the inner faces of the wings, and bolts including clips and nut locks for holding the 60 head plates firmly secured to the wings. 65

6. The combination with a series of ties each having oppositely directed apertured wings at its ends, of plates secured at their 70 ends to the opposing wings of adjacent ties, whereby to retain the ties properly spaced and prevent dislodgment of the ballast.

7. The combination with a series of ties each having oppositely directed apertured wings at its ends, of plates disposed between 75 the ties at their opposite ends, the opposite ends of each plate having apertures formed therein adapted to register with the apertures in the opposing wings of adjacent ties, and means disposed through the registering apertures to retain the ties properly spaced from each other. 80

8. The combination with a series of ties, of plates disposed between the ties at their opposite ends, the opposite ends of each of 85 the plates being secured to the ends of adjacent ties to retain the ties properly spaced and to prevent dislodgment of the ballast from between the same.

In testimony whereof I hereunto affix my 90 signature in the presence of two witnesses.

SETH CLELLAN GUNN.
